COMBINATION CHAIR AND TABLE

Ellsworth M. Towse, 80 Lowell St., Woburn, Mass.

Filed June 19, 1957, Ser. No. 666,682

3 Claims. (Cl. 155—123)

This invention relates to combination chair and table structures for infants.

It has heretofore been proposed to provide a collapsible table and chair wherein the chair is supported on a pair of spaced apart chair rails, or braces, and the table top is slideable above the chair rails as in U.S. Patent 2,725,094 to Goldblatt of November 29, 1955.

The object of this invention is to provide a table and chair of this type wherein the chair can be oscillatable or rigid and nonoscillatable in a number of positions ranging from sitting to reclining.

A further object of the invention is to provide a collapsible chair and table wherein the collapsible chair can be made rigid at will and in rigid condition can be used as a car chair.

Other objects and advantages of the invention will be apparent from the claims, the description of the drawing and from the drawing in which:

Fig. 1 is a side elevation, in section, of the combination chair and table showing in full lines the nonoscillating sitting position of the collapsible chair and in dotted lines one of the many nonoscillating sitting or reclining positions of the chair.

Fig. 2 is a side elevation of the chair in rigid, non-oscillatable sitting position and adapted for use as a car seat.

Fig. 3 is a rear view of the device shown in Fig. 2, and

Fig. 4 is an enlarged fragmentary plan view of the front, or cross, bar hinge and clamp means of the invention.

In the drawing, 20 is the collapsible table and 21 the collapsible chair of the invention. The table 20 includes a rectangular frame having side frame pieces such as 22 which include slots such as 23 for a slideable table top 24, the table top having a body opening 25. Table 20 also includes a pair of longitudinally extending, laterally spaced, parallel, chair rails 26 and 27 (see Fig. 4) for slideably supporting the chair 21. A plurality of oppositely disposed, spaced apertures such as 28 extend along each chair rail for selectively receiving a pin, or pins depending from the chair 21 to lock the same at various longitudinal positions on rails 26 and 27. The table legs such as 30 and 31 each preferably include a caster 32, a tubular portion 33 telescopic in a tubular portion 34, a socket 35 fixed at a corner of the table and resilient latches such as 36 and 37 for removal, locking or adjusting the height of the legs. A resilient latch 38 is provided on table 20 for locking the slideable table top 24 in position.

The collapsible chair 21 includes a frame 40 having two side members, a rear member and an opening at the front. Preferably the frame 40 is of hollow tubular metal of recumbent U shape with the opposite legs 41 and 42 forming the side members, the curved portion 43 forming the rear member and there being the opening 44 at the front of the frame. The legs 41 and 42 are laterally spaced to be slideably supported on the chair rails 26 and 27 and when table top 24 is in closed posi-

2

tion it closely overlies the legs 41 and 42 to prevent the lifting of the frame from the rails 26 and 27.

A detachable front, or cross, bar 46 is arranged to extend laterally across the opening 44 of frame 40 to connect the forward ends 47 and 48 of the side members, or legs, 41 and 42. The bar 46 includes a downwardly extending pin such as 49 or 50 at each opposite end thereof adapted to enter corresponding holes in the forward ends 47 and 48 and thence to enter oppositely disposed apertures such as 28 in rails 26 and 27 to selectively lock the chair frame 40 in various longitudinal positions. Preferably each pin 49 and 50 forms the terminal end of a hook such as 52 or 53, the forward end 48 includes a side hole 54 and a bottom hole 55 and the forward end 47 includes a slot 56 and a bottom hole 57. The pin 49 may thus be hooked into side hole 54 and bottom hole 55 to form hinge pivot means for the limited sidewise and downward movement of the bar 46 as well as a lock means. The forward end 47 includes a knob 58, a knob shank 59 threaded in the forward end 47 and a jaw member 60. The pin 50 and hook 53 may thus be lowered into slot 56 until the pin enters hole 57 and an aperture 28 whereupon knob 58 is turned to clamp the hook 53 between jaw member 60 and the side 61 of slot 56.

Collapsible chair 21 includes a seat 64 having a back 65 hingedly connected thereto by hinges such as 66. A pair of front and rear, spaced apart parallel, unitary hangers are mounted on each side of chair 21 such as the hangers 67 and 68 and the hangers 69 and 70. The hangers 67 and 69 thus are the forward hangers and the hangers 68 and 70 are the rearward hangers. The hangers are identical and the upper end of each hanger is pivoted as at 72 to a leg such as 42 and the lower end of each hanger is pivoted as at 73 to the seat 64.

A flexible strap 74 is attached below the front of seat 64 and to the middle point of front bar 46, the legs of the infant straddling the same to prevent sliding off the seat. Strap 74 is not, however, relied upon to prevent oscillation of the chair in the various positions ranging from sitting to reclining. Instead, locking straps 76 and 77 of rigid material, is provided for this purpose on each opposite side of chair 21. The rigid locking straps 76 and 77 are each preferably identical in length with the hangers such as 67 and each locking strap is pivoted at its lower end on the pivot axis such as 73 of the forward hangers 67 and 69. A female snap fastener 78 or 79 of a well known type is provided on the free terminal upper ends of each locking strap 76 and 77 and a male snap fastener 81 and 82 is mounted on the inside of the forward hangers at the pivots 72. The locking straps may thus be snapped into a position alongside the forward hangers when free oscillation of the chair is desired.

A second set of male snap fasteners 83 and 84 are mounted on the inside faces of opposite intermediate points along the rearward hangers 68 and 70 and adapted to receive fasteners 78 and 79. As shown in full lines in the drawing, when the locking straps are attached to fasteners 83 and 84 the chair 21 ceases to be collapsible and becomes rigid and non oscillatable in a sitting position. Thus when an infant is lowered into the chair table, the chair presents a rigid support which tends to allay the fears of the child and makes feeding easier.

A male snap fastener such as 85 is also positioned on the inner face of each rail 26 and 27 to receive the female fasteners 78 and 79 when the chair is to be in the reclining position shown in dotted lines in Fig. 1. In this position the chair 21 is rigid and non oscillatable and the child can be lowered into the chair with the connector 74 disconnected to avoid having to direct the child's legs on each opposite side of the same. By attaching the rigid

locking straps to the fasteners 85 and then sliding the frame 40 to various positions along rails 26 and 27 various angles of recline can be achieved depending on the number and spacing of the apertures 28.

A foot rest 89 and calf rest 90 are supported on a pair of apertured members 91 and 92 pivotally connected to the seat 64 at 73 and having a projection such as 93 adapted to engage the rear edge of the forward hangers. Thus the angle of the foot and calf rests change with the angle of the hangers and the foot rest 89 may be located in desired apertures by means of wing bolts such as 94, upon which it is also pivotable for foldability.

The chair back 65 includes spaced clips 96, 97, 98 and 99 for turnably supporting a pair of elongated car hooks 100 and 101 on the rearward face thereof. Each car hook such as 100 extends the full height of the back 65, the hooked portions 102 and 103 being attachable over the back of an automobile seat and the lower terminal end portions 104 and 105 being bent at substantially right angles to form arms which extend under the seat 64 when the hooks are turned from a flatwise position against the back 65 to a position normal thereto. When the locking straps 76 and 77 are fastened as shown in Fig. 2 and the chair is in rigid sitting position, the bent portions, or arms, 104 and 105, are resiliently received in the clips 106 and 107 mounted under seat 64 and detachably locked in position. It should be noted that the front bar 46 may be removed with its pins 49 and 50 when the device is used as a car seat so that the legs 41 and 42 become smooth chair arms and there is no rigid cross bar against which the infant might be thrown. A pair of D rings 107 and 108 are provided on the rear face of back 65 together with a safety belt not shown which may be passed through space 110 between the back 65 and seat 64 and encircled around the infant's body for safety and support purposes.

It should be noted that the hooks 100 and 101 serve as convenient handles for turning the arms 104 and 105 from the inoperative position shown in full lines in Fig. 1 to the operative position shown in dotted lines in Fig. 1 and in full lines in Figs. 2 and 3. When the arms 104 and 105 are in locking engagement in the clips 106 and 107 the car hooks maintain the angular relation of the back 65 to the seat 64 even though the straps 76 and 77 are released, the seat pivoted to the position shown in dotted lines in Fig. 1 and the straps 76 and 77 refastened to the snaps 85. The back of a very small infant may thus be firmly supported for sitting, with the seat in the forward, raised, dotted line position of Fig. 1, or the handles 100 and 101 may be turned to release the arms 104 and 105, thereby permitting the back 65 to fall rearwardly onto the portion 43 of frame 40, the back 65 being so shown in dotted lines in Fig. 1.

I claim:

1. In a combined table and chair for infants, the combination of a pair of parallel, longitudinally extending, laterally spaced chair rails each mounted along an opposite side of the upper portion of said table; a chair mounted for longitudinal sliding movement on said rails, said chair including a frame supported on said rails, two pairs of parallel hangers of rigid material depending from said frame and a chair seat supported at the terminal ends of said hangers for free, longitudinal, oscillating, movement relative to said frame; a chair back pivotally mounted on said chair seat for free longitudinal oscillating movement relative to said seat; means on said frame and chair rails for locking said frame in selected longitudinal positions relative to said rails, means on said hangers and chair rails for locking said chair seat in selected positions of oscillation relative to said frame, and means on said chair back and seat for locking said back in an upright position relative to said seat in any of the aforesaid selected positions.

2. A combination as specified in claim 1 wherein said means on said hangers and chair rails for locking said chair seat in selected positions of oscillation relative to said frame comprises a pair of locking straps of rigid material, each pivoted to the terminal end of one pair of said hangers and each having its opposite end connectable to the opposite end of said hanger, to the middle of the adjacent hanger or to the forward portion of the adjacent chair rail.

3. A combination as specified in claim 1 wherein said means on said chair back for locking said back in an upright position relative to said seat comprises a pair of car hooks extending the full height thereof and turnably mounted thereon, each having a lower terminal end portion bent to form an arm which extends under said seat when said hook is turned from flatwise position against said back to a position normal thereto and clips under said seat for detachably locking said arms to said seat.
